UNITED STATES PATENT OFFICE

HARRISON S. BURSON, OF ROCKY RIVER, OHIO

KEY CONTAINER

Application filed August 6, 1931. Serial No. 555,524.

This invention relates to key cases and has for its principal object the provision of a container wherein the keys may be positioned within a common case and associated with a mechanism for exposing any particular key without disturbing the normal position of the remaining keys. An additional object is to provide a case, which is well adapted for holding keys of different length and for retaining them in such manner that the case comprises a comparatively thin, flat package that can be conveniently carried in the pocket or hand bag of the user.

Referring now to the drawing, Fig. 1 is a side elevation of a key case embodying my invention; Fig. 2 is a top plan view of the same; Fig. 3 is a section taken on the line 3-3 in Fig. 2; Fig. 4 is a section on an enlarged scale taken on the line 4-4 in Fig. 2 and Fig. 5 is a section taken on still a further enlarged scale on the line 5-5 of Fig. 4.

I carry out my invention by providing a flat case with partitions which define pockets into which the various keys are adapted to be placed. Such case preferably comprises a U-shaped outer member 10, with partitions 11, which divide the container into pockets 12. In the preferred arrangement, the partitions are welded or otherwise suitably fastened to the bottom wall 13 of the casing 10 and are thereby held in upright parallel relationship. Furthermore, the partitions preferably have portions 14 thereof struck outwardly therefrom for engaging the sides 35 of the keys and holding them in place.

The keys indicated at 15 are disposed within the pockets and are pivotally mounted on the casing at 16. In the form shown, there are five keys within the case, two of which are pivoted at one end, and the remaining at the other end of the casing. The pivotal connection embodies a removable unit, which enables the keys to be readily positioned within the case or removed therefrom. The connection shown comprises a tubular member 20, which is internally threaded and is adapted to be inserted into the case from one end thereof, and an externally threaded member 21 which is adapted to engage the threads of the member 20, and to be inserted

therein from the opposite side of the case. Any form of pivot, however, may be utilized for removably holding the keys in place.

To facilitate ejection of the keys I prefer to mount a spring 25 in the bottom of each pocket and to utilize a leaf spring which is adapted to be loaded when the key is pressed downwardly into its pocket. I then provide a latch mechanism for holding the spring in loaded position, with a releasing device for unlocking the latch and thereby releasing the spring. The released spring then overcomes the friction of the partitions and forces the associated key out of the pocket, so that it is immediately available for use.

The preferred latch arrangement comprises a flexible member 26, which is anchored, as at 27, to the adjacent partition, but on the side opposite the associated spring. The upper end of the latch is provided with a tongue 28, which is adapted to extend through a notch 29 in the partition, and to engage the flattened end portion 30 of the spring 25 when it is loaded. The latch may be actuated by a thumb button 31, which is disposed on the outer end of a spindle 32. Such spindle extends through openings in the outer casing and partition and is rigidly connected at the inner end thereof to the latch 26. The normal set of the metal which forms the latch tends to keep the tongue thereof disposed in the path of the spring 25, so that after the thumb button is pressed inwardly to release the spring 25, the latch is returned to the normal position, as soon as the pressure is released.

To retain the key within the holder, even though the latches may be inadvertently operated while the case is being carried in the pocket of the user, I have shown a flexible strap 35, one end of which is anchored to the side of the case and the other end of which is adapted to be detachably fastened to the opposite side of the case as by a snap fastener 36.

An advantage of my invention is the fact that the bottom engagement of the key by its associated spring adapts the holder for keys of different length and provides a simple,

compact mechanism, by which the ejection may be accomplished. Furthermore, any particular key may be withdrawn from the case without disturbing the relative position 5 of the other keys.

I claim:

1. A key holder comprising a container having a pocket therein, a key disposed within the container and pivotally mounted adjacent 10 one end of the container, a spring positioned in the bottom of the pocket and adapted to be engaged and depressed by the key, a latch engaging the spring for holding the spring in loaded position, and a member positioned outside the container and attached to the latch for enabling it to be actuated to release the spring.

2. A key container, having a pocket opening outwardly from one edge thereof, a spring 20 carried by the container within the pocket, and adapted to be loaded by movement of the key into the pocket a latch engaging the spring to hold the spring in the loaded position, and means operable from the exterior 25 part of the casing for releasing the latch, said spring being adapted when released to eject the key from the container.

3. A key holder comprising in combination a container, having a plurality of partitions therein, means for pivotally supporting a key within each pocket, means associated with the partitions for frictionally engaging the keys and holding them within the container, a spring adapted to engage 35 the bottom edge of each key and means for holding the spring loaded independently of the key, said means being releasable from a point exteriorly of the container.

4. A key holder comprising in combination 40 a container, a key pivotally mounted therein, means for frictionally engaging the side of the key and for holding it within the container, a spring beneath the key, a latch for holding the spring in loaded position independently of the key, and a member connected with the latch and projecting outside of the container, said member being operable to release the latch, whereby the loaded spring 45 is released and the key is ejected from the container.

5. A key container comprising a casing having a partition therein, said partition having a key pocket, a latch, a key pivotally mounted within the pocket, a spring also 55 mounted within the pocket, a latch disposed on the side of the partition opposite the pocket and having a portion thereof extending through the partition and adapted to engage the spring and to hold it in loaded position, and a member disposed exteriorly of the container and attached to the latch, said member being adapted when operated to release the latch, whereby the spring may be 60 released and the key forced thereby out of the pocket.

6. A device of the character described, comprising in combination, a container having a pocket therein, a key pivotally mounted at one end thereof and adapted to be disposed within the pocket, a leaf spring carried by the container, a yieldable latch engaging the spring for holding the spring in loaded position and means outside the container for actuating the latch to release the spring whereby the spring operates to eject the key 70 from the pocket.

7. A key holder comprising in combination, a casing having a plurality of partitions therein for dividing it into a plurality of compartments, means for supporting a key in each of the compartments, a spring associated with the casing adjacent the bottom of each compartment, said spring being loaded by movement of a key into the compartment, each of said springs having a portion 80 adapted to engage the bottom of the associated key and a portion spaced from the bottom of the key, a latch for each compartment carried by the partition and adapted to enter the space between the spring and key for holding the spring in loaded position, and means outside of the casing for selectively operating the latches to release the associated springs.

In testimony whereof, I hereunto affix my signature.

HARRISON S. BURSON.
